COMBINED BROODER AND RUNS

Harley Holdredge, Valley Center, Calif.

Application March 28, 1946, Serial No. 657,785

4 Claims. (Cl. 119—34)

1

My invention relates to the art of poultry raising and more particularly to a means of brooding and raising young fowl, for instance, turkeys, hereinafter referred to as pouls.

In conventional brooding practice, two vital considerations governing the success or failure of the grower are temperature and cleanliness. Young pouls are extremely sensitive to temperature variation. Thus where the temperature falls below certain minimums, the pouls pile one atop the other for warmth, and loss is occasioned to the grower through smothering. Also where the temperature within the brooder becomes elevated to unseasonable heights, the pouls suffer, losing appetite and energy and fail to gain weight, frequently succumbing for this reason.

Many brooders have been built incorporating temperature control means utilizing, for instance, gravity heating, battery heating, and the like. Disadvantages attendant upon this type of heating are lack of flexibility in adapting a heater unit for varying numbers of brooder units, complexity of control requiring the services of several caretakers, and lack of capacity for the handling with one heater unit of large numbers of pouls.

In attempts to provide cleanliness in conventional brooders as concerns feed and water and in order to prevent the pollution of each other by the pouls, devices such as paper covered tread floors, feeding means, and dewdrop water systems in certain combinations have been heretofore resorted to. These have, however, been found to occasion the necessity of having several caretakers engaged in servicing the brooders, and in addition the tread floor is a frequent source of "spraddle leg" among the pouls.

In so far as is concerned cleanliness in the air, a noticeable feature in conventional brooding practice is the lack of provision for free circulation about the poult. The modern incubators of today consist of a heating element and one or more fans for circulating air around the eggs and pouls as they are in the process of incubation and hatching. Generally, following hatching in such a forced draft incubator, the pouls are held in boxes from twelve to twenty-four hours before putting them into the brooding system, after which they are considered in suitable condition for such brooders which, as heretofore stated, consist of a different environment than that undergone by the pouls during hatching; i. e., circulating fresh air is lacking. Such lack of circulating air not only makes necessary the work attendant upon taking the chicks into and

2

out of the boxes, but subjects them to a change in environment. Again dead air and dead air spaces within the brooders, besides failing to accomplish the function of hardening the pouls and causing feathering thereof, provide a means of infection.

One of the more serious problems confronting the grower is the disease Heximita, which accounts for thousands of young pouls each year. The spore of the germ of this disease, besides existing in contamination about the floor of the brooder, is to a large part present and developing in stagnant air, and where such spore-laden air is allowed to remain within the brooders during the spore development serious consequences may ensue.

Another disadvantage found in the conventional brooding systems is met in the relative immobility of the brooder or, if mobility is present, in its small capacity, since the ordinary brooder, unless of such small capacity, is incapable of being moved from place to place except by the efforts of a number of caretakers.

The object of my invention is to provide a clean, well ventilated brooding system of large capacity, operating on a forced draft principle in combination with runs for the raising of large numbers of young fowl under such circumstances that few caretakers are necessary and between broods the brooding system may be moved about with extreme ease.

It is my further object to provide in my brooder means for circulating warm dry air or, if conditions warrant, cool air, continuously through a number of brooders, the number of said brooders being easily variable and determining the capacity of my brooding system.

It is my further object to provide means for controlling the aforementioned heating of the circulating air through simple automatic thermostatic means placed in one of the brooding compartments whereby the said control of the heating requires a minimum of servicing.

It is another of my objects to provide a brooder having a high cleanliness factor over existing conventional brooders. In addition to providing continuously circulating air and thus substantially removing the menace of spore-laden Heximita, feeding and watering means are present in my brooder in such combination that the pouls will not pollute each other, while poult droppings may be easily removed through a paper roller device which does not induce "spraddle leg" in the young pouls. Likewise, no fecal matter can gain access to either feed or water, and the water is

so placed that poult traveling from the brooder compartments to the feed hoppers and vice versa must pass under such water. It is well known that almost every bird that passes under a drop of water hanging from a convenient place, such as a dewdrop pipe, will stop and drink. The experienced operator will recognize immediately that so encouraging the poult to drink will save many hatches.

It is a further object of my invention to provide the above means of feeding, watering, cleaning, and controlling temperature easily serviced by the caretaker. Access to all runs and to within the brooding compartments is simple and thus the cleaning thereof is facilitated.

Yet another object of my invention is to provide the same easily dismantled and thus readily portable.

Other objects and advantages of my invention will be apparent from the following description of the preferred embodiments thereof.

In the drawings:

Figure 1 shows a schematic plan view of my brooding system.

Figure 2 shows a cross section of my brooding system taken on the line 2—2 of Figure 1.

Figure 3 is an enlarged sectional and elevational view of my brooding system taken on the line 3—3 of Figure 1.

Figure 4 shows an enlarged cross section of my brooder heating unit taken on the line 4—4 of Figure 1.

Figure 5 shows a perspective view of my brooder unit and run.

Figure 6 shows a perspective view of some of my brooder units and runs showing the system set up to accommodate the older poult.

Figure 7 shows in part an enlarged sectional view taken through the line 7—7 of Figure 3.

Referring to the drawings, my brooder system in general comprises a heating unit 1, roofed brooder units 2 extending on either side of the said heating unit 1, poult runs 3 leading from the said brooder units 2, and poult runs 4 leading from the said runs 3 as extensions thereof. The heating unit 1 is adapted to supply air through the conduits 5 and 6 to the brooder units 2 wherein are kept the poult at night or during cold weather. Egress is permitted the poult to the runs 3 and, as will hereafter be explained, older poult to the runs 4, for feeding and watering.

More specifically, the heating unit 1 comprises a roofed heating shack 8 which encloses a stove 10. The stove 10 may be of a kerosene type circulating air heater into which air is introduced by a blower 12. The air passes through the circulating chamber 14 and heated air is forced into the cross member 16 which has a cap 18 and into the conduits 5 and 6 which seat thereonto. The cross member 16 may contain an emergency heater 20 consisting of electric heating elements, either manually or automatically controlled. The electric heating elements of said emergency heater 20 may comprise conventional resistant heating means suitably connected to a source of electric current and adapted to heat up upon application of said electric current and thereby heat the air passing through the cross member 16 in case of failure in the stove 10. A fuel tank 22 is adapted to supply kerosene or other fuel to the stove 10 in common manner. The temperature of the air flowing into the conduits 5 and 6 may be automatically

controlled by the wafer or thermostatic control unit 24. The thermostat 24, which is a common device, is automatically set and controls the amount of fuel consumed by the stove 10. It should be placed in proximity to the poult and may be in any one of the brooding units 2. The conduits 5 and 6 have orifices 23 cooperating with slip collars 25 to adjustably allow the passage of air into the brooder units.

Extending from each side of the heating shack 8 are the brooding compartments 2. The brooding compartments 2 are supported by the sawhorses 26 which carry the joists 28 the outer members of which extend to form the frame members 30, and supported by the joists 28 and the frame members 30 are the transverse frame members 32. The joists 28 likewise carry the subfloor 31 which extends through the slots 33 in the frame members 30 for a purpose to be later described.

Dividing each brooding unit are the walls 34 which have openings 36 through which extend and by which are supported the conduits 5 and 6. The walls 34 are supported by the frame members 30 and by the transverse frame members 32 and extend toward the runs 3 to the forward walls 35. The forward walls 35 have openings 38 over which hangs the "hover cloth" 40, the "hover cloth" being a common insulating material which retains heat within the brooding unit while permitting the poult to pass thereunder or through slits therein to the runs. Opposite the walls 35 are the walls 42 which, with roof 43 and floor, complete the enclosure of each brooding unit. The walls 42 have therein access doors 44 which enable the caretaker to reach any part of the enclosed brooding unit, and said doors 44 are provided with vents 46 to provide ventilation. It is to be noted that at the extremities of the conduits 5 and 6, doors 48 and 50 are provided to close off the said conduits while permitting the addition of further conduits to accommodate additional brooder units.

The brooder unit floor 52 consists of mesh hardware cloth carried by the nether edges of the walls 34, 35, and 42 in such fashion that, when the brooder compartments are lifted from the supporting frame members, the floor 52 is carried therewith. Such floor 52 permits the free passage of air from the conduits 5 and 6 around the poult. Over the conduits 5 and 6 are provided the hovers 56 which are constructed of light metal or similar flexible material and which are placed over the conduits 5 and 6 in such manner that the forward ends of the said hovers 56 are supported by the cleats 58 which are carried by the walls 34, and the rear ends of the said hovers are carried by the pivoted cleats 60 which are likewise mounted on the walls 34. The pivoted cleats 60 enable the caretaker to permit the rearmost ends of the hovers 56 to resiliently spring upward in such manner as to allow more height for additional growth of the poult. The forward ends of said hovers 56 are so affixed to the cleats 58 that the caretaker, upon freeing the said rearward ends of said hovers, may draw the hovers rearwardly, releasing the forward ends thereof and permitting said forward ends to resiliently spring upward similarly to the action of the rearward ends. Under the floor 52 are provided the paper belts 62 which are carried on roll forms 64 mounted in shack 8 in common manner, and which are adapted to carry away the droppings of the poult by the caretaker's pulling the ends

66 out to a desired length. The ends 66 pass through the slots 33 in the frame members 30, and the paper belts 62 are supported by the subfloors 31.

Adjacent the walls 35 and extending beyond the hover cloth 40 are the runs 3. The runs 3 comprise the walls 70 which may be suitably framed screens supported by the frame members 30 and the cross members 72. The floor of the runs 3 is an extension of the floor 52 and such extension is carried by the walls 70. Gates 76 are provided to close off the runs 3 and are supported by the transverse frame member 32, being comprised of suitably framed screens. Such gates 76 coact with the walls 70 and are held in place by the latches 78. The latches 78 are carried by a cross member 79 which is supported by the walls 70. Adjacent the gate 76 is provided a dewdrop water system comprising the dewdrop pipe 80 which may be raised and lowered at will by crank 82 which turns roller 84 from which is suspended the said dewdrop pipe. The said dewdrop pipe is well known in the poultry art and comprises a water-containing pipe having spaced valve outlets actuatable by the pouls and described in Patent No. 1,811,375 entitled Poultry Drinking Fountain, issued June 23, 1931 to Stewart Wyson. Rollers 84 are rotatably supported in suitable bearings carried by the walls 70, and if desired the pouls may drink from the said dewdrop system directly through the screen mesh of the gate 76 although ordinarily, when the pouls are too young for the addition of the runs 4 and the consequent removal of the gate 76, they will be watered by conventional pans and the like.

When the pouls have reached a suitable age, usually in seven or eight days, the gates 76 are removed and the runs 4 brought into coaction with the runs 3. The runs 4 are supported in manner substantially the same as are the said runs 3, sawhorses 86 carrying the frame members 87, the transverse frame members 88, and the joists 89. Since a subfloor such as subfloor 31 is unnecessary in this part of my brooding system, the joists 89 are of the same width as the frame members 87. The floor 92 of the runs 4, similar to the floor 52, consists of mesh hardware cloth and is mounted upon the lower edges of the walls 94. The walls 94 comprise suitably framed screens, the forward portions of which constitute double walls which are divided horizontally by the cross members 96 and are screened at their upper portions 98. Said screening need be on but one side of the double wall. The lower portions of the said double walls are adapted to retain slidably the feed troughs 100 which are carried by the floor 92 and which may be extended through the apertures 102 in the end members 104 of the walls 94. Cross beam 106 is supported by the walls 94 and carries the members 108 which with floor 92 and walls 94 provide gateways for the gates 110, said gates comprising suitably framed screens and being supported by the transverse frame member 98 and latched by the latch 112 on the members 108. In order to accommodate the dewdrop pipe 80, it is noted that the walls 94 do not have sufficient length to abut the walls 70 but rather permit a slot therebetween in which the said dewdrop pipe 80 rides.

Positive connection between runs 3 and 4 is achieved by bolting the transverse frame members 88 to the transverse frame members 32 together through aligning holes 114. If desired, chicken wire 116 or other covering may cover the

runs 3 and 4, being carried by the walls 70 and 94 and being secured by cross beams 106 and 118.

The operation of my brooder is apparent from the foregoing description. The newly hatched pouls may be taken directly from incubator to brooder and placed within the compartments 2. If warmth is desired, the heating unit 10 will supply a continuous circulation of fresh, dry, warm air. While very young, the pouls will, of course, be fed by hand, passing through the openings 38 for this purpose. The brooding compartments 2 may be kept at constant temperature by virtue of the thermostatic control 24. After seven or eight days, the runs 4 are brought up to the brooding system and bolted on. The pouls are thus given an extended run and are enabled to be conveniently fed by means of the feed troughs 100. To reach the runs 4, the pouls must travel under the dewdrop pipe 80 and will thus be induced to water. Cleaning of the brooding system is facilitated in that all parts thereof may be easily reached and in that paper 62 is being continuously changed. When the pouls are of an age suitable for removal from the brooding system, it may be quickly dismantled by unbolting the transverse frame members 88 and 88, lifting the component parts of the runs 4 from the sawhorse and frame member supports, detaching the conduits 5 and 6 from the cross member 16, and lifting the brooding compartments 2 and component parts of the run 3 from their respective sawhorses and frame members.

Having fully described my invention, it is to be understood that I do not wish to be limited to the details herein set forth, but my invention is of the full scope of the appended claims.

I claim:

1. A device of the class described, comprising: supporting means; a row of brooding compartments carried thereby; runs in side by side relationship carried thereby and extending from said brooding compartments; feed troughs slidable between said runs; and overhead watering means between said feed troughs and said brooding compartments, said watering means including a roller pulley extending transversely over said runs and rotatably supported thereby and a dewdrop pipe suspended from said roller pulley.

2. A device of the class described, comprising: supporting means; two frame assemblies carried thereby and including longitudinal and transverse frame members; a row of brooding compartments seating on said first frame assembly, said brooding compartments including a rear wall, a front wall having openings therein, compartmenting walls, a roof, and a meshed floor carried by said rear, front, and compartmenting walls; a row of runs coacting with said openings in said front wall, said row of runs including side walls and a meshed floor carried by said side walls; a second row of runs coacting with said first row of runs and seating on said second frame assembly, said second row of runs including side walls, a meshed floor carried by said side walls, and feed troughs slidably extendable between said runs; and overhead watering means between said brooding compartments and said second row of runs.

3. A device of the class described, comprising: supporting means; two frame assemblies comprising longitudinal and transverse frame members; a row of brooding compartments seating on one of said frame assemblies; a straight conduit passing through each of said brooding compartments and opening thereinto; means for cir-

culating air through said conduit and into said brooding compartments; a row of runs seating on the same frame assembly as does the row of brooding compartments; and coacting therewith, said row of runs including side walls and a meshed floor carried by said side walls; a second row of runs coacting with said first row of runs and seating on said second frame assembly, said second row of runs including side walls, a meshed floor carried by said side walls, and feed troughs slidably extendable between said runs; and overhead watering means between said brooding compartments and said second row of runs.

4. A device of the class described comprising: a brooding compartment adapted to house pouls; a run extending therefrom, said run including a food compartment; and overhead watering means between said brooding compartment and said food compartment, said overhead watering means being so disposed that said pouls necessarily pass under said watering means in traveling from said brooding compartment to said food compartment.
